[57] CLAIM

The ornamental design for a screw holding attachment for a screwdriver, as shown and described.

DESCRIPTION

FIG. 1 is an exploded side elevational view of the screw holding attachment for a screwdriver showing my new design;

FIG. 2 is a side elevational view thereof, the opposite side being identical;

FIG. 3 is a top plan view thereof;

FIG. 4 is a bottom plan view thereof.

The broken line showing of the screwdriver is for illustrative purposes only and forms no part of the claimed design.
